UNITED STATES PATENT OFFICE.

CHARLES D. KAUFMANN, OF CHICAGO, ILLINOIS, ASSIGNOR TO KAUFMANN & FABRY CO., OF CHICAGO, ILLINOIS, A CORPORATION OF ILLINOIS.

PROCESS OF PRODUCING FOLDERS.

Application filed July 16, 1924. Serial No. 726,374.

To all whom it may concern:

Be it known that I, CHARLES D. KAUFMANN, a citizen of the United States, and a resident of Chicago, Cook County, and 5 State of Illinois, have invented certain new and useful Improvements in Processes of Producing Folders, of which the following is declared to be a full, clear, and exact description.

10 This invention relates to the process of producing folders and its principal objects are economy, saving of time and labor, and neatness and elegance in the finished article.

This invention has particular reference to 15 folders that contain photo prints usually mounted on a strip of fabric or paper backing in such manner that the strip may be folded between the photo prints so as to condense the size of the strip, whereby a number of the folders may be bound in a cover 20 and carried in the pockets of one's wearing apparel.

Ordinarily considerable time is required, 25 in the manufacture of the ordinary folder of this type, and great precision and accuracy was required to mount the prints on the backing so as to produce a finished article.

30 With the present process, less expert workmen may be employed in the production of the folder, and a more attractive finished article is produced.

With these and other objects in view, this 35 invention consists in the novel features hereinafter fully described and claimed.

The invention is clearly illustrated in the accompanying drawing, in which:—

Fig. 1 is a face view of a printed and developed photographic strip containing a 40 plurality of individual photographs thereon; Fig. 2 is a face view of said strip after certain slotting operations have been performed thereon; Fig. 3 is a face view of said strip partly broken away, after it has been mounted on a backing, trimmed and 45 certain round cornering operations have been performed thereon; Fig. 4 is an edged view of the strip, and Fig. 5 is a perspective view showing a number of the finished 50 folders bound in a cover.

In carrying on the present process, a plurality of spaced individual photographs are first made on an elongated sensitized strip of suitable dimensions slightly greater than 55 the finished article. The strip is developed,

fixed and dried in the ordinary manner. Thereafter the strip is slotted transversely between the photographs at equidistant places. The slotted strip is then mounted on a suitable backing formed of cloth, or 60 other fabric, paper, vellum or the like, the edges trimmed, and, if desired the corners of the individual photographs rounded off. The strip is then prepared for binding in a 65 cover.

Referring to the accompanying drawing, which illustrates a folder in the various stages of its formation, the reference character 10, designates an elongated print strip having spaced individual photographs 11 70 made thereon by the photographic process, and an extra space 12. The photographs may portray commercial objects or they may be artistic or of domestic subjects as is desired. The entire strip is developed, 75 fixed and washed and thereafter dried on a ferrotype or squeegee as is customary in the art of producing photographic prints.

After the print strip is dried, it is slotted 80 transversely between the photographs 11 by suitable dies, at equidistant places, as at 13, (see Fig. 2) to form the spaced side edges of the hereinafter mentioned individual prints 14. The slotted print strip is then 85 damped or wetted and mounted on a backing 15 formed of cloth, or other woven fabric, paper, vellum or the like, by pasting it thereto and drying it on a ferrotype or squeegee. The strip is then folded along 90 lines between the edges of the individual prints 14 and trimmed along the lines $x-x$, $y-y$ (Fig. 3) to form the edges of the finished folder. The corner portions of the prints are then rounded off as at 18 by suitable dies, thereby connecting the side edges 95 17 with the end edges 16 by round corners. In Fig. 3 at the left end thereof, part of the strip is shown in its condition before the corners of the individual prints have been 100 rounded, and at the right end, the strip is shown in its finished condition. The part 12 at one end of the strip is prepared for binding the strip in a cover, and this is ordinarily done by punching holes 21 therein with suitable dies. In Fig. 5 is shown a 105 cover 19 having a number of the folders bound therein. Said cover may be provided with the ordinary temporary binder screws 20 for securing the folders thereto and it may be arranged to wrap around the 110

folded strip, and may have a clasp for securing the flaps of the cover together.

It will be observed that individual photographic prints are thus adapted to be mounted on a backing, which photographic prints are spaced equidistant, are parallel with each other and present a neat, elegant and effective appearance. Moreover all of the prints may be made simultaneously on a sensitized strip from one or more negatives. Furthermore, by slotting the strip and leaving uncut portions along the top and bottom of the strip all of the prints remain connected together during the wetting, mounting and drying operations, which insures the proper positioning of the individual prints on the backing. In trimming the upper and lower edge portions, the cuts may be made along the ends of the slots, if desired, but in order to give a more handsome appearance to the folder, the cuts are made beyond the slots, and the corners are rounded as shown. The fabric backing forms hinge like parts between the individual prints, upon which the latter may be folded to condense the length of the strip.

I claim as new and desire to secure by Letters Patent:

30 1. The herein described process of producing folders, which consists in transversely slotting a strip, having spaced indi-

vidual photographs printed thereon, mounting the slotted strip on a backing, and trimming off the edge portions of the strip and 35 backing back to the slots, thereby leaving separated individual photographic prints mounted on a backing which is foldable between the prints.

2. The herein described process of producing folders, which consists in transversely slotting a photographic strip, having spaced individual photographs printed thereon, mounting the slotted strip on a backing, trimming the edges of the strip 40 and backing, and round cornering the corners at the ends of the slots to leave separated individual photographic prints, mounted on a common backing, which is foldable between the prints. 50

3. The herein described process of producing folders, which consists in transversely slotting a strip containing printed individual photographs, and a blank space, mounting the slotted strip on a woven fabric 55 backing, trimming off the edges of the strip and backing, round cornering the corners at the ends of the slots to leave separated individual spaced prints and a binding member mounted on a common backing 60 which is foldable between the prints, and perforating said binding member.

CHAS. D. KAUFMANN.
